Primary Examiner — Michael A. Pratt

(74) Attorney, Agent, or Firm — Thomas | Horstemeyer,
LLP(57) **CLAIM**The ornamental design for loudspeaker enclosure, as shown
and described.**DESCRIPTION**1.1 is a perspective view of an embodiment of a loudspeaker
enclosure, showing my new design;

1.2 is a front view thereof;

1.3 is a rear view thereof;

1.4 is a side view thereof;

1.5 is a side view thereof, from a side opposite that of 1.4;

1.6 is a top view thereof;

1.7 is a cross-sectional view thereof;

2.1 is a perspective view of another embodiment of a
loudspeaker enclosure, showing my new design;

2.2 is a front view of the loudspeaker enclosure of 2.1;

2.3 is a rear view of the loudspeaker enclosure of 2.1;

2.4 is a side view of the loudspeaker enclosure of 2.1;

2.5 is a side view of the loudspeaker enclosure of 2.1, from
a side opposite that of 2.4;

2.6 is a top view of the loudspeaker enclosure of 2.1; and

2.7 is a cross-sectional view of the loudspeaker enclosure of
2.1.**1 Claim, 14 Drawing Sheets**(56)
